(57) **CLAIM**

The ornamental design for an electronic piano, as shown and described.

DESCRIPTION

FIG. 1 is a perspective view of an electronic piano according to a first embodiment showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of an electronic piano according to a second embodiment showing my new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken line showing of the electronic piano is included for the purpose of illustrating portions of the electronic piano and forms no part of the claimed design.

1 Claim, 10 Drawing Sheets
